SELECTIVE PUNCHING AND DISPENSING MECHANISM

Virgil A. Turner, Blair S. Alden, and Frank S. Alden, Anna, Ill.

Application February 12, 1949, Serial No. 75,994

4 Claims. (Cl. 312—87)

1

This invention relates to a new and improved selective punching and dispensing mechanism.

Numerous types of punches and dispensers have been made and used for many years. In a manufacturing operation it is often necessary to place material to be punched between the operator and the punching tool making it difficult if not impossible to know the position of the punching tool and thus also know where the material will be punched. Further, in coin operated dispensers of small pellets such as medicinal capsules or the like it has been a problem to select the desired pellet and then have it discharged merely upon the insertion of a coin.

It is therefore a principal object of this apparatus to provide a punching tool having a beam or ray extending in a path in alignment with the center line or longitudinal axis of the punching tool to thereby indicate the position of the punching tool.

An important object of this invention is the provision of means associated with a punch to make known the geographical position of the punch.

Another important object of this invention is to provide means in a dispensing mechanism for selecting by visible indicating means any one of numerous objects or articles to be dispensed.

Another important object of this invention is to supply means for selectively punching portions of a light transmitting material.

Another and further important object of this invention is the provision of a punching tool having an integral source of light therein and means for confining and directing the beam formed thereby in alignment with the longitudinal axis or line of movement of the punching tool.

Still another object of this invention is to provide means in a combination dispensing and punching apparatus for shiftably moving the punching device with respect to the articles to be dispensed and thereby selectively dispensing any one of the desired articles.

Another and still further important object of this invention is to provide an enclosed dispenser of small articles having means for selecting one of the articles and thereafter discharging the selected article to a position of access outside the enclosed dispenser.

A still further important object of this invention is the supplying of automatic indexing means for a punching tool with reference to both horizontal and vertical directions in an article dispensing machine.

Still another object of this invention is to pro-

2

vide electrical solenoid punch projecting means in combination with a dispensing mechanism.

Other and further important objects of this invention will become apparent from the disclosures in the following specification and accompanying drawings.

In the drawings:

Fig. 1 is a perspective view of the dispensing mechanism of this invention.

10 Fig. 2 is a front elevational view of the device of Fig. 1 with the front door and magazines thereof removed.

Fig. 3 is a sectional view taken on the line 3—3 of Fig. 2.

15 Fig. 4 is a sectional view taken on the line 4—4 of Fig. 2.

Fig. 5 is a top plan view of the device as shown in Fig. 1.

20 Fig. 6 is a sectional view taken on the line 6—6 of Fig. 2.

Fig. 7 is a sectional view taken on the line 7—7 of Fig. 2.

Fig. 8 is a sectional view taken on the line 8—8 of Fig. 2.

25 Fig. 9 is an enlarged detailed sectional view of the punching element of this invention.

As shown in the drawings:

The reference numeral 10 indicates generally a housing or supporting structure employed to carry and enclose the dispensing elements of this invention. The enclosure 10 includes a box-like portion of side walls 11 and 12, a rear wall 13, a top 14 and a bottom 15. A door 16 is hingedly mounted by hinge means 17 and 18 on the side wall 11, and constitutes the front wall of the boxlike enclosure 10. Suitable lock or latch means may be employed to hold the door 16 in closed position with respect to the housing 10.

As explained above, one of the more important objects of this invention is the provision of means for dispensing by selection any one of numerous articles that may be placed in a board or the like. This board is shown at 19 and includes a plurality of regularly spaced openings 20 extending through the board from the front to the back thereof. The board 19 is removably mounted within the supporting structure 10 between vertically disposed frame members 21 and 22. Many small items or articles for sale may be placed within the apertures or holes 20 in the board 19, and dispensed by the mechanism of this invention. Further, as mentioned above, the articles dispensed may be such as medicinal capsules of various types and may be positioned over the board in any manner desired. The dispenser

is designed for self use and thus does not require the presence of an attendant or store clerk. As shown in Figures 1, 3 and 4 the replaceable and/or refillable board 19 is visible through a transparent window or the like 23 in the front door 16. The door 16 is further provided with a slot 24, extending across the front of the door beneath the window 23 and extending through to the inside of the housing 10. A tray 25 is placed within the transversely disposed slot 24 and is arranged to receive articles dispensed by the mechanism for placing the article selected within reach of the user. As shown in Fig. 3, the board 19 is further provided with upper and lower frame members 26 and 27, respectively, for forming a complete peripheral frame therefor to give adequate support to the removable board 19.

As best shown in Fig. 2, shaft means 28 and 29 are disposed across the housing and between the side walls 11 and 12 adjacent the top 14 and bottom 15 respectively. These shaft means 28 and 29 are parallel one to the other, and are widely spaced apart. Each shaft means 28 and 29 comprises horizontally spaced shaft members 28a and 28b, and 29a and 29b respectively.

The cross shaft members form tracks for lateral shifting of a vertically disposed shaft member 30. As best shown in Figs. 2, 6 and 7, the vertical shaft member 30 is journaled for rotation in a carrier member 31 at the bottom of the housing 10 and in a carrier 32 adjacent the top of the housing. Each of the carriers 31 and 32 is provided with spaced, horizontally disposed apertures arranged in the same spaced apart position as the shaft members 29a and 29b, and 28a and 28b respectively, whereby the carriers 31 and 32 may slide transversely along and over the shaft members 28 and 29. As shown in Figs 2 and 3, the shaft 30 continues upwardly beyond the carrier 32 and extends out through the top 14 of the housing 10 through an aperture 33 provided therefor. A knob 34 is fastened to the shaft 30 and is adapted to provide a hand engaging means for effecting rotation of this vertically disposed shaft 30. The shaft 30 as shown in Fig. 2 is provided with a spiral or helical groove 35. A channel member 36, as shown in Fig. 4 has its U-member enclosing the vertically disposed shaft 30. The channel 36 extends between the carrier members 31 and 32, and is fixed at its ends to each of these carrier members. For convenience in describing this device, the shaft 30 and its surrounding channel 36 will be termed the vertical structure adapted for transversely sliding movement within the housing 10.

A block member 37 is adapted to be carried by the vertical structure, and is movable vertically on the spirally grooved shaft 30 by reason of a sleeve portion 38 having an inwardly extending spiral rib coincident with the spiral groove in the shaft 30. This sleeve 38 is fixed to the block 37, and thus the two elements move together. It will thus be seen that as the shaft 30 is rotated, the block 37 and the sleeve 38 with its inwardly extending rib 39 engaging the spiral groove 35 will move either up or down on the shaft 30. The upper and lower ends of the block 37 are provided with enlarged annular flange members 40 and 41 respectively. An outer sleeve or the like 42 is carried intermediate the ends of the block 37. Spring members 43 and 44 of substantially equal strength are disposed between the sleeve 42 and the top flange 40 and between the sleeve 42 and the bottom flange 41, respectively, to maintain

the sleeve 42 centered between the ends of the block 37.

As best shown in Figures 2 and 3 the sleeve 42 is provided at its forward portion with a transversely disposed hole or opening 45. This hole 45 receives the shank end 46 of an indexing element 47. The rod portion 46 is positioned within the opening 45 for lateral sliding movement. A spring 48 is located within the slot 45 behind the shank 46 and urges the indexing member 47 outwardly in a lateral direction from the sleeve 42. The carriers 31 and 32 additionally support an index rack 49 as best shown in Figure 2 which is equipped with a plurality of notches 50 on its one vertical face thereof. The notched rack 49 is affixed to the carrier members 31 and 32 so that the rack moves as a unit with the vertical structure as it is slid transversely along the cross shaft members 28 and 29. The indexing member 47 has a ball like end 51 engaging the rounded notches 50. The spring 48 urging the indexing member 47 outwardly insures contact of the indexing member with the rack 49.

It will be evident from Fig. 4 of the drawings that the block 37 may not rotate with the shaft 30 for the reason that it closely surrounds the rectangularly shaped non-rotatable channel 36. Rotation of the knob 34 will cause a raising or lowering of the block 37 and thus also the sleeve 42. However, the sleeve with its indexing means will have a tendency to delay immediate movement by reason of the ball end 51 engaging the notches 50 in the indexing rack. In operation the block 37 moves upwardly or downwardly and one or the other of the springs 43 or 44 will be compressed. Thus for example if the block 37 is moved upwardly by rotation of the knob 34 the lower spring 44 will be compressed until it reaches a certain predetermined compression whereupon it overcomes the holding by the indexing means and the sleeve 42 will follow upward movement of the block 37 in a sort of jumping action. This jumping action makes certain that the sleeve 42 will lie in a plane opposite one of the notches 50 in the indexing rack 49.

As best shown in Fig. 2 a similar indexing rack 51' is provided across the top of the supporting structure 10 and further has a series of notches 52 on the underside thereof. The carrier 32 for the upper end of the vertical structure is equipped with a spring held indexing member 53 adapted with a ball like end 54 for engagement with the notches 52 in a manner very similar to the engagement of the ball end 51 of the indexing member 47 with the notches 50 in the vertically disposed indexing rack 49. The indexing member 53 is disposed vertically in a vertical opening or slot 55 within the carrier 32. A spring 56 is positioned beneath the indexing member 53 within the opening 55 and urges it upwardly. Thus in moving the vertical structure laterally by a movement of the knob 34 within and along the elongated slot 33 in the top of the supporting structure or enclosure 10 as best shown in Figure 1 the vertical structure will come to rest in a position in alignment with one of the notches 52.

The dispensing board 19 with its many apertures 20 is preferably made in such a manner that the apertures are disposed in horizontal and vertical lines and spaced similarly to the notches 50 in the vertical indexing rack 49 and with the notches 52 in the horizontal indexing rack 51'. By reason of this construction 75 it is assured that the means for dispensing the

contents of each aperture may be made certain. As shown in Figs. 2 and 4 the punching or dispensing element and its projecting means is fastened to the sleeve 42 which as previously explained is spring mounted on the block 37 and is maintained in alignment with one of the indexing notches 50. The entire punching element unit will be designated by the numeral 57. The outer shell like portion 58 constitutes an electrical solenoid within which is carried a piston like member 59 acting as the movable member of the solenoid. This internally positioned piston 59 is shown in detail in Fig. 9. The forwardly disposed end 60 is tubular in shape and is of sufficiently small diameter to pass through the apertures 20 in the board 19 for forcing out the articles to be dispensed. The piston 59 is shown in its innermost position with respect to the dispensing board 19 and it will be understood that upon supplying the solenoid 58 with electrical energy the piston 59 will be moved suddenly forwardly causing the forward or punch end to move through the aperture 20 behind which it is positioned. The central portion of the piston 59 is designated by the numeral 61 and provides a socket 62 for an electrical lamp or bulb 63 having a screw threaded base 64 engaging the socket 62. The bulb 63 is positioned within the tubular punching end 60 of the piston 59. The central portion 61 is of considerably greater diameter than the end 60 and thus easily houses the bulb 63. The cone shape of the piston at the portion 65 immediately adjacent the bulb 63 confines and directs the beam or ray from the bulb to and through the end 60 of the piston element 59. As shown in Figure 9 the piston 59 is also provided with a rearwardly extending tubular portion 66 forming a continuation of the enlarged central portion 61. Electrical conducting wires 67 and 68 are carried through the hollow end of the portion 66 and join with the socket 62 at 69 and 70 to thus carry electricity to light the bulb 63.

As best shown in Figs. 3 and 4 a spring 71 surrounds the rearward end portion 66 of the piston 59 and is anchored at spaced points at 72 on the solenoid 58 and at 73 on the piston 59. This spring 71 normally urges the piston 59 rearwardly in the solenoid or jacket 58. It will thus be seen that after the solenoid has been energized and the punching element 59-60 moved suddenly forwardly, the spring 71 will then cause the piston 59 to resume its normal rearward position.

As best shown in Fig. 3 an electrical attaching member 74 is adapted to engage a source of electro-motive-force and conduct electrical current and energy through the wires 67 and 68 for lighting the bulb 63. In addition a second electrical circuit is provided through the electrical connecting element 74 through parallel wiring means 75 and 76. The wire 75 runs to a switch element 77, and the wire 76 extends to the solenoid 58. The switch member 77 is provided with a connecting wire 78 which joins with the electrical solenoid 58. Thus when the switch means 77 is closed the solenoid 58 will be electrically energized and the punching element 59-60 moved forwardly.

The switching element 77 is composed of a pair of contact members 79 and 80. When these contact points 79 and 80 are brought together the electrical circuit to the solenoid 58 is completed thus causing the piston to lunge forwardly moving the article in the board positioned in

front of the punch to be discharged. The device of this invention is equipped with a coin slot 81 on the top of the housing 10. The coin slot is in alignment with the contact member 80 and as a coin is dropped through the slot 81 it moves the contact member 80 inwardly toward the contact member 79 making momentary contact with the element 79 and completing the electrical circuit as just described. The coin inserted through the slot 81 continues its downward movement in the housing 10 to a receptacle 82 located in the bottom of the box. A door 83 having a hinge 84 at the bottom thereof and a hand engaging knob 85 at the top is for the purpose of gaining access to the receptacle 82 to effect removal of the coins therefrom. Here again suitable locking means may be used to hold the door 83 closed against the public users of this dispensing mechanism. It is obvious that a more complex coin mechanism may be employed to insure against the use of slugs or spurious coins without departing from the invention.

In the operation of this device the electrical plug means is attached to some electrical power outlet and immediately the bulb 63 within the punching element is lighted causing a ray of light to emerge from the punching element at 60. This ray of light is in alignment with the longitudinal axis of the piston 59 and further is coincident with the path of movement of the punching element 60. When the board 19 is placed within the housing 10 as previously described the location of the punching element 60 would not ordinarily be determinable. The light 63 used within the punching element obviates this difficulty and indicates the position of the punching element to the operator or user of this dispensing mechanism. It will be understood that the articles to be dispensed must have at least some light transmitting means and therefore when the operator of the machine desires to effect a discharge or removal of any of the elements or articles to be sold which are lodged in the apertures of the dispensing board 19 he moves the punching element to a selected position by the knob 34 on the top of the housing 10. Lateral movement of the knob within the elongated slot 33 causes corresponding lateral movement of the punch and rotation of the knob 34 causes the punching element to move upwardly and downwardly with respect to the board as desired. As previously described the indexing means insures that the punching element will be in proper alignment with one of the many apertures 20 in the board. The user of the vending device can tell where the punching element is by reason of the light ray being visible on the front face of the board. After the user has selected the article he desires to purchase and has placed the punch in a position immediately behind that article by proper movement of the knob 34 he inserts a coin in the slot 81 causing the solenoid 58 to be momentarily energized and the punch 60 to move forwardly causing the article within the aperture 20 to be pushed forwardly out of the board 19 and thereupon to drop vertically downwardly between the board 19 and the window 23 to the receiving tray 25. The user or operator may thereupon pick the article out of the tray 25 within the transversely disposed opening 24.

We are aware that numerous details of construction may be varied over a wide range without departing from the principles disclosed herein and we therefore do not propose limiting the

patent granted hereon otherwise than as necessitated by the appended claims.

What is claimed is:

1. A machine for selectively punching light beam transmitting portions of a board comprising a supporting structure for removably carrying boards to be punched, a punching element, means for adjustably positioning said punching element in any desired location on said supporting structure with respect to said board to be punched, an electric bulb mounted within said punching element, a circular electrical solenoid positioned around said punching element, spring means attached to said punching element and said supporting structure and normally urging said punching element to a retracted position, an electrical switch, a source of electrical energy, wiring means connecting said electric bulb with said source of electrical energy, and wiring means connecting said electrical solenoid, electrical switch, and source of electrical energy in series, whereby when the electrical switch is closed the punching element with its light therein will be projected against the action of the spring means centrally within said circular electrical solenoid against said board causing discharge of a portion thereof.

2. A machine for selectively causing dispensing of light transmitting articles positioned in a board in which the articles are arranged in horizontal and vertical lines, comprising a supporting structure for removably carrying boards of articles, a punching element carried by said supporting structure, means for moving said punching element in alignment with any one of the articles on said board, light beam means associated with said punching element to cause visible effect on the face of the board to indicate the position of the punching element, said means for moving the punching element comprises a vertically disposed structure arranged for horizontal sliding movement in said supporting structure, said vertically disposed structure includes a stationary member and a rotatable shaft, a hand engaging means on the top of said rotatable shaft for lateral shifting of the

vertically disposed structure and rotating of the rotatable shaft forming part thereof, said shaft having a spiral groove affixed thereto over the length thereof, a non-rotatable block slidable vertically on said vertically disposed structure, said punching element carried on said block, said block having a cooperative internally spiral ribbed portion engaging the spiral groove on the shaft whereby the hand engaging means is slid laterally for horizontal adjustment of the punching element and/or rotated for vertical adjustment of the punching element.

3. A machine as set forth in claim 2 in which notched indexing racks are positioned both horizontally and vertically in said supporting structure with the notches thereof in alignment with the horizontal and vertical lines of the articles, first releasable detent means on said vertically disposed structure for engaging the notches in the horizontal notches rack, and second releasable detent means on said block for engaging the notches in the vertical notched rack.

4. A machine as set forth in claim 3 in which yieldable spring means is provided intermediate the punching element and the block to cushion both up and down movements whereby indexing of the punching element is facilitated.
